UNITED STATES PATENT OFFICE

157,203

CHILD'S PLAYSUIT

Mary Piecka, Braeburn, Pa.

Application June 4, 1948, Serial No. 146,755

Term of patent 14 years

(Cl. D3—17)

To all whom it may concern:

Be it known that I, Mary Piecka, a citizen of the United States of America, residing at Braeburn, in the county of Westmoreland and State of Pennsylvania, have invented a new, original, and ornamental Design for a Child's Playsuit, of which the following is a specification, reference being had to the accompanying drawing, forming a part thereof, wherein:

I claim:

The ornamental design for a child's playsuit, as shown.

MARY PIECKA.
